UNITED STATES PATENT OFFICE.

PETER MALACOS AND STEVE CANELLOS, OF CONNELLSVILLE, PENNSYLVANIA.

PAPER-HANGING DEVICE

1,348,290.

Specification of Letters Patent. Patented Aug. 3, 1920.

Application filed November 1, 1919. Serial No. 334,950.

To all whom it may concern:

Be it known that we, PETER MALACOS and STEVE CANELLOS, subjects of the King of Greece, and residents of Connellsville, county of Fayette, and State of Pennsylvania, have invented certain new and useful Improvements in Paper-Hanging Devices, of which the following is a specification.

10 This invention relates to paper hanging devices, and it has for its primary object to provide an improved construction of tool by means of which paste may be applied to a strip of wall paper as the latter is unwound from the roll and by means of which such strip may be conveniently applied to a wall.

20 A further object is to provide a structurally improved and simplified device of the type disclosed in the patent to Malacos, No. 1,288,093, dated December 17, 1918.

The invention resides in the structural features and combination which will hereinafter be described, reference being had 25 to the accompanying drawings, in which—

Figure 1 is a side elevation of the invention;

Fig. 2 is a sectional perspective view of the paste reservoir and paste-applying roller;

30 Fig. 3 is a perspective view of the supporting frame; and

Fig. 4 is an elevation of the back of the paper-applying brush.

Referring to the said drawings, in which 35 like designating characters distinguish like parts throughout the several views—

1 indicates the opposite similarly-shaped side members of a supporting frame, and 2 a transverse member rigidly connecting the 40 front ends of said side members, said transverse member having attached thereto a suitable form of handle, as 3. Said members 1 have formed thereon or provided therein suitable rests, as those constituted 45 at the inner ends of the curved slots 4, upon which may be seated the opposite reduced ends of a removable roller 5, adapted for carrying a roll 6, of wall paper.

Disposed between and carried by the side 50 members 1 of the frame is a casing 7, preferably of sheet metal, which, as herein shown, is approximately rectangular in cross section, and which is designated as a reservoir or container for a liquid adhesive 55 or paste that is to be applied to the reverse

surface of the strip 8 of paper as the latter is unwound from the roll 6.

The reservoir 7, is formed with a longitudinally-extending outwardly-facing trough 9 in its rear edge portion, said edge 60 portion having an approximately semi-circular form in cross section. Fitted more or less snugly in said trough is a roller 10 which is provided with a covering 11 of felt, velvet or other suitable material, preferably velvet carpeting or other material having a long nap. Said roller 10 has reduced ends 12 journaled in suitable bearings, as those afforded by brackets 13 mounted upon the ends of the reservoir. 70

Provided at suitable intervals in the casing wall constituting the trough 9 are perforations 14 through which the liquid paste feeds to said roller 10.

Superposed over or upon the top of the 75 casing at a suitable point is a brush 15 over which the paper strip 8 passes and whereby the paste applied by the roller 10 to said strip is evenly distributed over the surface of the latter.

80 Mounted in the front or upper, ends of the side members 1 are the ends of a paper-applying brush 16 which is so arranged that the bristles thereof are properly located for utilization for applying yielding pressure to 85 the paper strip as the latter is applied to the wall, said strip leading from contacting relation with the brush 15 to and under the brush 16 and thence upward in front of the latter. 90

As shown in Fig. 1, as the paper strip is unwound from the roll 6, it is passed rearwardly to and upward over the roller 10, thence over and in contact with the spreader brush 15, thence to, under, and upward in front of the brush 16. In passing over said roller 10, the strip frictionally engages and produces rotation of said roller resulting in the application to the adjacent face of said strip of a coating of the paste which exudes 100 upon said roller through said perforations. 95

The brush 16 is so disposed that the paper strip contacts directly with the under side of its head 16^a. To provide for the prevention of buckling of the paper and the smoothing 105 out of any small wrinkles appearing therein, the under side of said head 16^a, is made slightly convex, or inclines upward slightly toward its opposite ends from an approximately central point, as shown in Fig. 4. 110

What is claimed is—

1. In a paper hanging device, a mounting for a roll of paper, a paste reservoir having an approximately flat top surface, said reservoir being disposed over said mounting, a sealing brush located over the forward end of said reservoir, said reservoir having its rear wall reentrantly curved in semi-circular form to provide an outwardly and upwardly facing trough, said trough being provided with perforations, and a paste-applying roller rotatable in said trough and substantially conforming to the contour of the latter, said roller being so located with respect to the position of the paper roll and said brush that, in unwinding from said roll, paper is drawn over said roller and thence passes in a substantially horizontal direction over said flat surface of the reservoir to and under said brush.
2. In a paper hanging device, a mounting for a roll of paper, a paste reservoir disposed over said mounting, said reservoir having its rear wall reentrantly curved

whereby is formed exteriorly of the reservoir a rearwardly facing trough, said trough having perforations opening thereinto through said curved wall, a paste-applying roller rotatable in said trough and supplementing the latter to provide a regularly curved convex path for the travel of the paper over the rear end of the reservoir, a paste-distributing brush over which said paper passes after leaving said roller, and a brush mounted over said reservoir in position to apply sealing pressure to the paper as the latter is passed in front thereof from the first-mentioned brush, the last mentioned brush having the paper contacting surface thereof provided with a convex curvature transverse to its axis.

In testimony whereof we affix our signatures in presence of two witnesses.

PETER MALACOS.
STEVE CANELLOS.
